UNITED STATES PATENT OFFICE.

SAMUEL S. SENCENBAUGH, OF AURORA, ILLINOIS.

CARTON.

1,254,163.

Specification of Letters Patent. Patented Jan. 22, 1918.

Application filed April 2, 1915. Serial No. 18,655.

To all whom it may concern:

Be it known that I, SAMUEL S. SENCENBAUGH, a citizen of the United States, residing at Aurora, Kane county, Illinois, have 5 invented certain new and useful Improvements in Cartons, of which the following, taken in connection with the drawing, is a description.

My invention has for its object the production of a carton or package-container 10 designed to be used in stores of various kinds where packages are to be wrapped and delivered to customers. This carton is especially adapted for inclosing suits, overcoats, 15 dresses, etc., which require careful handling and should be wrapped so that there will be no unnecessary creasing or disarranging of the articles contained in the package.

A further object of my invention is to 20 provide a package which will contain the articles and one which is provided with the necessary fastening devices to close and secure the parts together and provide at the same time a handle for carrying the package 25 in the manner of a suit case.

A further object of my invention is to 30 provide such a carton which is formed of a single piece of material so shaped that it may be laid upon a flat surface and packed 35 closely together for shipment, the material out of which the carton is made being creased and cut at the proper places to enable the user to readily form the carton by bending the sides and ends into the shape 40 required to form the carton and secure the parts together with the means provided therein for doing so.

In the accompanying drawings I have 45 illustrated what I now consider the preferred forms of my invention, although it is obvious the details of the same may be changed without departing from the spirit of my invention, which consists essentially in providing a package container of a single 50 piece of material and having means thereon for securing the same together and providing a handle by means of which the package may be carried. In these drawings,

Figure 1 represents a plan view of my 55 package container having the sides and one end thereof spread out to show the formation of the same, and one end folded into the position occupied by it when the carton is closed;

Fig. 2 is a vertical, sectional view of the 55 folded carton; and

Fig. 3 is a perspective view of the same.

Referring to the drawings, A', represent the blank or material of which the carton is formed, which may be paste-board or any 60 other material suitable for the purpose.

The bottom of the box, B', is cut to whatever size is desired. a, a', are scored or weakened lines on the board forming the carton, and these are measured to the proper 65 dimensions to form the sides, C, C, of the carton. The free ends of the blank, A', A', are formed of the proper length so that when the carton is folded one of the edges will overlap the other and form the top of 70 box or carton as hereinafter explained.

At each end of the bottom of the carton B', is an extended portion, D', D'. Scored or weakened lines d², d³, are provided across the end portions D', arranged the same distance apart as the line a', a', to form when folded the ends C', C', of the cartons. A tongue e, projects from each side of the end portions D', D', which is adapted when folded to close the corners of the carton. 80

In the form of construction shown, I have 85 illustrated the end portions D', D', as triangular in shape, the point of each triangle being provided with one part of a fastening device, c, c, so that when the ends D' are folded inwardly to close the package 90 the ends overlap and are secured together by the fastener c, c. The separate parts of the fastening device c', c', are arranged in the portions A', A', and adapted when folded into a carton to secure the two sides together to close the package.

Through one edge of the carton I secure 95 the rivets H or other securing members having heads thereon. Attached to these securing members and extending between the same is a handle H'. One end of a tape or cord h, is adapted when the carton is folded and the fasteners secured, to be passed around the body of the carton, as shown in 100 Fig. 3, and returned to the securing member H and wound around the same to secure the cord in position.

In forming the carton from the flat strip 105 of paste-board which has been cut to the shape shown, the goods to be placed in the carton are laid in the bottom of the box B', the tongues e, e, are bent at right angles

to form the corners, and the ends D', are bent along the creased lines d^2 , d^3 , to form the ends of the carton.

It will thus be seen that I have provided 5 a carton or package-carrier, which is exceedingly simple in construction and which provides a receptacle for packages with facilities for carrying the same which the ordinary box or bundle does not have.

10 I claim:

A carton formed of a single piece of material divided by scored or weakened lines into section adapted to be bent to form a receptacle, the opposite end portions being 15 triangular in shape, the point of each triangle having fastening means attached

thereto whereby the ends may be folded inwardly to close the package with said ends engaging each other, tongues projecting from the sides of said piece of material to 20 be folded to form closed corners, and cords attached to said carton and adapted to extend around the body thereof and be secured in place, substantially as described.

In testimony whereof I have signed this 25 specification in the presence of two subscribing witnesses.

SAMUEL S. SENCENBAUGH.
